UNITED STATES PATENT OFFICE.

GEORGE S. GALLAGHER, OF NEW YORK, N. Y., ASSIGNOR OF ONE-HALF TO HENRY GALLAGHER AND ONE-HALF TO EMMA G. GALLAGHER, OF NEW YORK, N. Y.

STEAM-BOILER FURNACE.

1,085,859.

Specification of Letters Patent.

Patented Feb. 3, 1914.

Application filed August 13, 1910. Serial No. 577,006.

To all whom it may concern:

Be it known that I, GEORGE S. GALLAGHER, a citizen of the United States, residing in the borough of Manhattan, city, 5 county, and State of New York, have invented a new and useful Improvement in Steam-Boiler Furnaces, of which the following is a specification.

My invention relates to improvements in steam boiler furnaces, with the object of improving and making more permanent, lasting and readily repaired the portion of the furnace in proximity to the coal doors. Heretofore, in these devices, the inner 15 surfaces of the coal doors have been built up of brick. These surfaces have been liable to injury from heat, abrasion and other causes, and it has been difficult to repair such parts, as there has been no means of 20 supporting the walls of the furnace above such location and during such repairs.

In the device of my improvement, I employ jamb-blocks of hollow cast metal with fire brick tile faces. The jamb-blocks are 25 built into the furnace wall at each side of the door, and the fire brick tile faces cover and protect the same, completing the continuity of the surfaces, which, when worn, damaged or broken, can be removed without 30 disturbing the wall or other parts and be replaced by new tiles, which are quickly put in place, and completely restore the structure, without loss of time and with a minimum of expense, all of which is hereinafter 35 more particularly described.

In the drawing, Figure 1, is a sectional plan through the front of a steam boiler furnace at the coal door illustrating the device of my invention; Fig. 2, is an elevation, as if the coal door and front plate of the furnace had been removed. Fig. 3, is a perspective view of one of the jamb-blocks from the inner corner thereof; Fig. 4, is a perspective view of the fire brick tiles employed over the side of this jamb-block, and Fig. 5, is a perspective view of the front tile for said jamb-block; Fig. 6, is a sectional plan similar to Fig. 1, also showing a form of my improvement, in which the steam 40 boiler furnace is provided with two similar doors, making it necessary to employ a spacing block between the doors; Fig. 7 is a perspective view of this spacing block; Fig. 8 is an end view and Fig. 9, a plan of 45 the same spacing block; Fig. 10, is a per-

spective view of the end or corner fire brick tile for the spacing block, and Fig. 11, is a vertical section through the end of this spacing block and fire brick tile, showing a modified form of construction.

In all the figures of the drawing, similar letters and numerals of reference indicate similar parts.

a represents the front metal wall of a steam boiler furnace and *a¹*, *a²*, the doors closing the coal openings into the combustion chamber of the furnace, which doors are of the usual construction, hung upon hinges and provided with latches for holding them closed.

b represents the dead plate occupying a horizontal position at the base of the doors and forming the surface over which the coal is shoveled into the furnace, and *c* represents an arch plate, which forms the top of the coal opening and is suitably supported at its ends, so as to hold up the front brick wall of the furnace over the coal openings, *d*, *d¹* are parts of the front brick wall of the furnace at either side of the coal doors, and *e* represents the grate-bars.

Referring particularly to Figs. 1 to 5, inclusive, as well as to the left-hand side of Fig. 6, *f* and *g* represent jamb-blocks, which come at either side of the coal opening of the furnace, rest upon the dead-plate *b* and come between the same and the arch plate *c*, so as to carry the ends of the arch plate and support the same and the brick wall above. The jamb-blocks shown have the same construction, but in reversed position and they fit into the right angle produced between the front wall *a* and the walls *d*, *d¹*. This jamb-block is hollow in shape, it is a quadrilateral figure, that is to say, there are two corners in horizontal section, which are right angles, there is one corner an obtuse angle, and one corner an acute angle. The jamb blocks are each provided with lugs *f¹*, *g¹*, through which and the front wall, bolts 2 are passed, which secure the jamb-blocks to the front wall *a*. Two of the vertical walls of these jamb-blocks, or, in other words, those exposed to the open part of the combustion chamber are preferably provided with horizontally disposed grooves 3 and perforations 4, the perforations coming at the bases of the grooves, and these jamb-blocks are also provided at the margins of the exposed faces with upwardly and 100

downwardly projecting tapering ribs 5 and 6, between which and the body of the jamb-block, are formed channels or grooves.

- 1 provide fire brick tiles *h* and *i*; there 5 may be two tiles *h* and one tile *i* to each jamb-block. The tiles *h* have parallel vertical faces and upper and lower parallel edges, which are grooved, with the inner edge shorter than the outer edges, and the outer 10 face of the tile agreeing in vertical depth with the complete depth of the jamb-block, consequently, the tile or tiles *h* are connected to the jamb-block, by slipping the same into position from the smaller end of the jamb-block toward the wider part with the ribs 15 thus brought into the grooves of the tile, so that the tile, when in position, cover and protect the ribs and surface the side of the jamb-block. The tile *i*, as will be seen from 20 Figs. 1 to 5 inclusive, is of a different shape from the tile *h*, having a flat face, which is adapted to lie against the face of the jamb-block and the end of the tile *h*, that would otherwise be exposed, and a curved vertical 25 outer face and an end, which comes up against either wall *d*, or *d'*, and is slipped into place toward said wall with the ribs 5 of the jamb-block in the groove of the tile, which protects the same.
- 30 Referring to Figs. 6 to 11, inclusive, the jamb-block and tile faces, shown on the left-hand of Fig. 6, are the same as have been just described with reference to Figs. 1 and 5, inclusive, but Fig. 6, illustrates that the 35 device of my invention, may be provided with two coal doors, *a'*, *a''* in which case the intermediate supporting device for the arch plates and the front wall of the furnace, is provided with the form of a spacing block 40 *h* in section of the form of a letter V, the broader end of which comes next to the front wall *a* of the furnace. This spacing block is advantageously connected to this wall by the lugs *f'* and the bolts 2, employed 45 for the jamb-blocks hereinbefore described. The spacing block is also provided with horizontally disposed grooves 3 and perforations 4, at the base of the grooves similar to the jamb-block, also with ribs 5 and 6 up 50 from the lower edge and down from the upper edge, similar to the jamb-blocks and fire brick tiles *l*, *l'* are employed, which are similar to the fire brick tiles *h* and are placed in position in the same manner, and 55 also an end fire brick tile *m* coming next to the combustion chamber of the furnace and placed in position similar to the tile *i*. These several tiles form faces to the jamb-blocks and spacing blocks, completely covering the 60 faces thereof, protecting them from the heat of the combustion chamber of the furnace. Should these fire brick tiles become burned out, worn out, or broken, they can very quickly be removed and be replaced by new 65 ones, slipped into position with the spaces

between the same filled with cement and this may be done at a minimum of cost and very quickly, without in any way disturbing the structure of the front wall of the furnace.

I prefer to employ means providing for the escape of the heat within the jamb-blocks, in addition to the grooves 3 and perforations 4, shown and described in connection with the jamb-blocks and spacing blocks, so that the pent up hot air within the jamb-blocks, or spacing blocks, may escape. For this purpose, in Figs. 1 and 2, I have shown holes 10 in the bottom of the jamb-blocks, which communicate with channels 11 built in the brick wall of the furnace and communicating with the ash pit below. In Fig. 6, I have for like purpose, shown holes 12 formed through the front wall *a* of the furnace, so that the hot air may escape into the atmosphere in front of the furnace, therefore, between these means, suitable ventilation is provided to keep the interior of the jamb-blocks and spacing blocks, as cool as possible.

In Fig. 11, I have shown the end tile *m* for the spacing block with a transverse horizontally disposed rib 13, adapted to be received in a channel formed in the end face of the spacing block, as an additional device 95 for holding the end tile *m* in position. This form of construction applies with equal force to the construction of the fire brick tile *i* and either jamb-block *f*, although, I do not limit my invention to the use of this 100 rib 13.

From Figs. 1 and 6, it will be apparent that the space between the dead plate *b*, the arch plate *c* and the side members of the front wall, which in the device of my invention, are the fire brick tiles, increases in width from the door or doors toward the combustion chamber, because of the inclination given to the jamb-blocks and the spacing block and their fire brick tile faces.

From the drawings, it will be noticed, that the corners of the ribs 5 and 6, are cut away, so as to provide for holding the fire brick tile in position and engagement with the jamb-blocks or spacing block.

I claim as my invention:

1. In a steam boiler furnace, a hollow spacing block tapering in plan from a larger to a smaller end and adapted to be built in the wall of a furnace with the smaller end toward the combustion chamber, marginal ribs in the smaller end and side portions on the said block extending upwardly from the lower part and downwardly from the upper part and spaced from the body of the block so as to provide grooves between the said ribs and the body of the block, and fire brick tiles provided with edge grooves adapted to receive the said ribs so that the tiles are moved hori- 130

zontally to place on the block, the tile at the smaller end of the block extending over the adjacent edges of the tiles at the side of the block and being provided with a rounded 5 outer surface.

2. In a steam boiler furnace, a spacing block adapted to be built in the front wall of the furnace and located between two coal doors, formed hollow and in plan in the 10 shape of a letter V with the pointed end toward the combustion chamber and provided with end marginal ribs extending up from the lower part and downwardly from the upper part and spaced beyond the body of 15 the said block, so as to provide grooves between the ribs and the body of the spacing block, and three fire brick tiles at the re-

spective sides and point of the spacing block all agreeing in height with the height of the spacing block and the said tiles having 20 grooves in the opposite edges to receive the ribs of the spacing block and to be slipped into position, two of said tiles covering and protecting the side faces of the spacing block and ribs thereof and one with 25 a rounded point extending across the ends of the other two tiles and the smaller end of the spacing block.

Signed by me, this 9th day of August, 1910.

GEORGE S. GALLAGHER.
